(57) **CLAIM**

The ornamental design for an airplane lavatory, as shown and described.

DESCRIPTION

FIG. 1 is a front, right perspective view of an airplane lavatory showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a sectional view taken along lines 8-8 shown in FIG. 2;

FIG. 9 is a sectional view taken along lines 9-9 shown in FIG. 2;

FIG. 10 is a sectional view taken along lines 10-10 shown in FIG. 6;

FIG. 11 is a sectional view taken along lines 11-11 shown in FIG. 6;

FIG. 12 is a sectional view taken along lines 12-12 shown in FIG. 6;

FIG. 13 is a sectional view taken along lines 13-13 shown in FIG. 6;

FIG. 14 is a front, left perspective view showing an interior part thereof; and,

FIG. 15 is a rear, left perspective view showing the interior part thereof.

The broken lines shown are included for the purpose of illustrating the unclaimed portions of the airplane lavatory and form no part of the claimed design.
